(57) **CLAIM**

The ornamental design for feminine self-administrable sampling and topical therapy device, as shown and described.

DESCRIPTION

FIG. 1 is a front perspective view illustrating my design for a feminine self-administrable sampling and topical therapy device;

FIG. 2 is a front view thereof;

FIG. 3 is a right side view thereof;

FIG. 4 is a top view thereof;

FIG. 5 is a left side view thereof;

FIG. 6 is a bottom view thereof; and,

FIG. 7 is a rear view thereof.
